Jakob Knoller

UNITED STATES PATENT OFFICE.

JAKOB KNOLLER, OF BERLIN, GERMANY.

BRUSH.

980,161.

Specification of Letters Patent. Patented Dec. 27, 1910.

Application filed November 4, 1908. Serial No. 461,094.

To all whom it may concern:

Be it known that I, JAKOB KNOLLER, a subject of the German Emperor, and resident of 73 Ritterstrasse, Berlin, Germany, have invented certain new and useful Improvements in and Relating to Brushes, of which the following is a specification.

My present invention relates to such brushes which are used wet *e. g.* tooth-brushes or hand-brushes or nail-brushes and it serves for the purpose to better and quicker clean and dry the single sets of bristles by moving the same apart for any suitable time so preventing a collecting of 10 injurious germs between the single bristles. For this purpose the part carrying the brush consists either of elastic waterproof material so that it may be accommodately bent and fastened in this bent form or the sets of 15 bristles can be placed on single rods which can be moved apart by any suitable means. The elastic waterproof brushes can be fixed after their use in a bent position between suitable arresting means fixed to the brush 20 holder.

The rods carrying the bristles may consist either of longitudinal- or of cross-rods. Some of these rods can be removed temporarily from the others in such a manner that 25 a rod with bristles alternates with a groove or cutting by which motion the desired separation of the single sets of bristles is attained. The separating of the single rods from each other can be effected by swinging, turning, pushing or bending the same 30 or in any other suitable manner.

In the accompanying drawing in which I have illustrated my invention like letters of reference refer to like parts throughout the 35 different views.

In said drawing, Figure 1 shows a perspective view of a tooth-brush in which the part carrying the brush is removed, Fig. 2 shows a perspective view of the part carrying the brush, Fig. 3 shows a perspective view of a tooth-brush in which the part carrying the brush is bent and arrested in this 40 position between pins fixed to the holder. Figs. 4-11 show other construction of fastening the part carrying the brush to the brush holder, Fig. 12 shows a side view of a hand-brush, Fig. 13 shows a side view of a hand brush the brush being removed from its working position, bent, and inserted into 45 grooves arranged on the back of the holder.

As shown in Figs. 1-3 the brush-holder 1

provides a guide 2 having fastening means *e. g.* pins or screws or projections or the like. These fastening means serve at one hand for the purpose to secure a safe fastening of the 50 body carrying the brush 4 hereafter called the brush, and at the other hand as stops for the elastic ends of the bent brush, preferably consisting of elastic and waterproof material. In Fig. 3 it is shown how the bent 55 brush 4 is inserted *e. g.* between the inner edge of the guide 2 and a pin 3.

Figs. 4, 5, and 6 show a form of construction of a tooth brush in which the brush-holder is provided with a dovetail like 70 guide 6. After the use of the brush the same is drawn apart of its holder 5 and the elastic ends of the bent brush 4 inserted into cuttings 7 and 8 of the guide (Fig. 6). The securing of the brush against dropping out 75 is attained by any suitable means.

Figs. 7, 8, and 9 show a form of construction of a tooth brush in which the brush holder 9 is provided with perforations 10 arranged always between two sets of bristles. 80 The brush 12 (Fig. 8) is inserted into the holder 9 by passing its bristles 13 through said perforations 10. In this construction it is not necessary to make the brush of elastic material as the same is not bent. The 85 fastening of the brush 12 to the holder 9 is attained in any suitable manner.

Figs. 10 and 11 show a form of construction of a tooth-brush in which the supporting end of the brush holder forms a three-pronged fork 15. The prongs 15 are provided with sets of bristles and along their inner side with grooves 16 into which fits the part 17 also carrying sets of bristles and providing guiding borders 18. The fastening of the parts 17 to the part 15 can be attained in any suitable manner.

Figs. 12 and 13 show a hand- or nail-brush. The fixing of the brush 21 to the plate 19 of the holder can be attained according to any 100 of the above described constructions. The handle 20 provides cuttings 22 into which the bent brush is inserted after its use.

The single parts of my improved brush can of course be changed in form and construction within the limit of my invention.

What I claim as new and desire to secure by a United States Letters Patent, is:—

1. In a device of the kind described, the combination of a brush holder and a flexible elastic brush detachably connected therewith, the holder being provided with means

to hold the brush in a bowed position for drying and cleaning it.

2. In a device of the kind described the combination of a brush holder and a flexible elastic brush detachably connected therewith, the holder being provided on its back with cuttings to hold the brush in a bent position for drying and cleaning.

In testimony whereof I have hereunto signed my name this 15th day of October 1908, in the presence of two subscribing witnesses.

JAKOB KNOLLER.
